UNITED STATES PATENT OFFICE.

GEORGE E. GREENLEAF, OF PLAINFIELD, NEW JERSEY, ASSIGNOR TO NILES-BEMENT-POND COMPANY, OF NEW YORK, N. Y., A CORPORATION OF NEW JERSEY.

TAILSTOCK CLAMPING MEANS.

Application filed November 25, 1925. Serial No. 71,353.

This invention relates to lathe tailstocks and particularly to a tailstock for lathes of intermediate size.

An object of the invention is to provide an improved form of clamping mechanism adapted to securely clamp the tailstock in any adjusted position along the bed of a lathe.

One feature which enables me to accomplish the above named object is that clamping plates are provided below the tailstock adapted to engage the ways of the lathe and held by bolts thereto, these clamps being in the form of levers adapted to have their inner ends forced downwardly to effect the clamping operation.

Another feature which is advantageous is that a toggle mechanism is provided on the tailstock engaging an equalizer member in contact with and adapted to press against the inner ends of the clamping levers.

Another object of the invention is to provide threaded means for forcing this toggle mechanism to its clamping or unclamping position.

With these and other objects in view, my invention consists in the features of construction and operation set forth in the following specification and illustrated in the accompanying drawing.

In the accompanying drawing annexed hereto and forming a part of this specification, I have shown my invention embodied in a tailstock for a lathe, but it will be understood that the invention can be otherwise embodied and that the drawings are not to be construed as defining or limiting the scope of the invention, the claims appended to this specification being relied upon for that purpose.

In the drawing:

Figure 1 is a side elevation of a complete tailstock, partly in section, and provided with the present invention.

Fig. 2 is a transverse sectional view taken on the line 2-2 of Fig. 1, and

Fig. 3 is a plan view of the clamping levers and equalizer member.

In the above mentioned drawing I have shown but one embodiment of the invention which is now deemed preferable, but it is to be understood that changes and modifications may be made within the scope of the appended claims without departing from the spirit of the invention.

Briefly, and in its broadest aspect, my invention comprises the following principal parts: first, a tailstock body member provided with a movable tailstock spindle; second, a pair of clamping levers below the tailstock and having their outer ends engaged under portions of the ways on which the tailstock is movable; third, bolts supporting these clamping levers in position and forming fulcrums about which they may oscillate; fourth, an equalizer member adapted to rest upon the inner or adjacent ends of the clamping levers; fifth, a system of toggle levers, one of which is supported within the tailstock body member and the other in the equalizer member; and sixth, threaded means for operating these toggle levers to move the clamping levers to clamping and unclamping positions.

Referring more in detail to the figures of the drawing, I provide a tailstock body member 10 which is adapted to be adjusted along suitable ways 11 of a lathe bed 12. Below the tailstock 10 and adapted to have their outer ends engaged under portions of the ways 11 are two clamping levers 13. These levers 13 preferably extend substantially the entire length of the tailstock 10 at their outer ends and have their inner or adjacent ends brought closely together below the mid line of the tailstock. The levers are supported by means of bolts 13^a passing upward through the tailstock 10 so that they are free to oscillate about the heads of the bolts as fulcrums. Above the adjacent or inner ends of the clamping levers 13 rests an equalizer member 14 which is held by means of toggle levers 15 and 16 in position and disposed so that it may be moved up or down by the movement of these toggle levers 15 and 16. In order to move these toggle levers 15 and 16 to clamp or unclamp the levers 13 against the ways 11, a rearwardly extending rod 17 is provided attached at its inner end to a cross pin 18 between the toggle levers 15 and 16. Rotatably mounted on this rod 17 is a threaded member 19 provided with screw threads of relatively long lead, this threaded member as shown being disposed between collars 20 on the rod 17 so that it may be easily rotated but cannot move longitudinally upon the rod. In order to rotate this threaded member 19, its outer end is provided with a handle 21 preferably keyed directly thereto.

- as shown in Fig. 2. The threaded member 19 engages threads within a nut 22 secured in position within the body member 10 of the tailstock.
- 5 In operation the equalizing member 14 may be forced downward to oscillate the clamping members 13 to rigidly secure the tailstock 10 in position by movement of the rod 17 into the position shown in full lines 10 in Fig. 2. To raise the equalizer member 14 and thus unclamp the levers 13 it is only necessary to rotate the threaded member 19 in the opposite direction to move the toggle levers 15 and 16 to the position shown in 15 dotted lines.

What I claim is:

1. A tailstock for lathes comprising in combination, a body member, a pair of opposed clamping levers below said body member and adapted to engage the lathe ways, an equalizer member engaging the contiguous ends of said levers, toggle levers attached to and supporting said equalizer member, and means to positively actuate 20 said toggle levers to move said clamping levers to clamping and unclamping position.
2. A tailstock for lathes comprising in combination, a body member, a pair of opposed clamping levers below said body member and adapted to engage the lathe ways, an equalizer member engaging the contiguous ends of said levers, toggle levers attached to and supporting said equalizer 25 member, and threaded means thereon adapted to positively actuate said toggle levers to move said clamping levers to clamping and unclamping position.
3. A tailstock for lathes comprising in combination, a body member, a pair of opposed clamping levers below said body member and adapted to engage the lathe ways, bolts 30 flexibly supporting said levers in position, an equalizer member engaging the contiguous ends of said levers, toggle levers attached respectively to said body member and equalizer member, and threaded means to positively actuate said toggle levers in 35 opposite directions to clamp and unclamp said tailstock.
4. A tailstock for lathes comprising in combination, a body member, a pair of opposed clamping levers below said body member and adapted to engage the lathe ways, bolts supporting said levers in position, an equalizer member engaging the contiguous 40 ends of said levers, toggle levers attached respectively to said body member and equalizer member, a transversely extending rod, and threaded means thereon adapted to positively actuate said toggle levers in opposite directions to clamp and unclamp said tailstock.

member, a transversely extending rod attached to the intermediate point of said toggle levers, and threaded means thereon to actuate said toggle levers to move said clamping levers to clamping and unclamping position.

3. A tailstock for lathes comprising in combination, a body member, a pair of opposed clamping levers below said body member and adapted to engage the lathe ways, bolts flexibly supporting said levers in position, an equalizer member engaging the contiguous ends of said levers, toggle levers attached respectively to said body member and equalizer member, and threaded means to positively actuate said toggle levers in 50 opposite directions to clamp and unclamp said tailstock.

4. A tailstock for lathes comprising in combination, a body member, a pair of opposed clamping levers below said body member and adapted to engage the lathe ways, bolts supporting said levers in position, an equalizer member engaging the contiguous ends of said levers, toggle levers attached respectively to said body member and equalizer member, a transversely extending rod, and threaded means thereon adapted to positively actuate said toggle levers in opposite directions to clamp and unclamp said tailstock.

In testimony whereof, I hereto affix my signature.

GEORGE E. GREENLEAF
